UNITED STATES PATENT OFFICE.

WILL F. JOHNSON, OF HARVARD, NEBRASKA.

COW-TAIL HOLDER.

1,413,587.

Specification of Letters Patent. Patented Apr. 25, 1922.

Application filed November 15, 1919. Serial No. 338,271.

To all whom it may concern:

Be it known that I, WILL F. JOHNSON, a citizen of the United States, residing at Harvard, in the county of Clay and State 5 of Nebraska, have invented certain new and useful Improvements in Cow-Tail Holders, of which the following is a specification.

The present invention relates to improvements in cow-tail holders devised with due 10 consideration of the conditions of use and application of an article of this character, the object of which is to provide means for preventing switching of the tail during milking, more especially.

15 I am aware that many devices along this line have heretofore been proposed but these possess features more or less impractical because of a lack of appreciation of the requirements looking towards facility of attachment and detachment, or prevention of displacement by the animal accidentally or deliberately.

For example, the previous devices which embody an adjustable leg encircling member 25 to surround the leg just above the gambrel joint are usually applied when the animal is standing normally and, failing to conform to the shape of the leg, this member permits forward movement of the leg 30 without difficulty, resulting often in kicking over the milk pail or injury to the milker. Likewise the cow is able to kick or move its leg rearwardly, which causes a contraction of the leg at the point of attachment and 35 permits the encircling member to drop down over the adjacent joint. On the other hand by making this element of my device to conform exactly to the contour of the cow's leg,—that is providing a portion in its circumference fitting closely about the gambrel cord, both forward and rearward movements 40 of the leg are precluded so that my invention becomes usable as an anti-kicking device.

45 Again, in many of these prior devices, it requires both hands to detach this leg member, when as a matter of fact, it is desirable to do this quickly while at the same time removing the clamp or tail holding member. Owing to the particular form of fastener which I employ, this may readily be 50 accomplished, one hand effecting release of the encircling band while the other hand releases the tail clamp.

55 A further feature of advantage in my particular device is the provision of a flexi-

ble connection between the two main holding elements so that a certain amount of movement of the tail is permitted in the absence of which the animal would naturally 60 become restive as when the tail is held rigidly against movement, as contemplated by certain of these prior devices, and this particular feature of my invention tends to maintain cleanliness of the device. 65

These and such other objects as may hereinafter appear are attained by the novel construction, combination, and arrangement of parts to be hereinafter specifically described and claimed. Reference will now be 70 had to the accompanying drawing forming a part of this specification, wherein:

Figure 1 is a top plan of a device constructed in accordance with my invention.

Figure 2 is a side elevation thereof. 75

Figure 3 is a sectional view on the line 3—3 of Figure 2; and

Figure 4 is a view showing the application of my invention in operative position.

Throughout the following detailed description and on the several figures of the drawings, like reference characters refer to similar parts. 80

Referring to the drawing, my invention consists of the leg encircling member or 85 band 1, the tail engaging clamp 2 and the intermediate flexible connection 3. The member 1 consists preferably of a light metallic strip, in order that the shape or configuration given thereto will retain its form, 90 the material having of course a certain amount of resiliency. At one end the band is reduced or pressed together so as to form the cord receiving seat 4 adapted to snugly fit about the gambrel cord of the cow's leg. 95 The band 1 is an open one and at the end of one side is pivotally secured the fastener hook 5 which is adapted to engage in any one of the series of openings 6 provided in the other side of said band. The fastener 100 referred to is of such a character that it may be very quickly slipped into place in the application of this member and much more quickly detached since it requires merely the lifting of the outer end of the hook to accomplish this end. When the band is applied to the leg of the cow it is adjusted to fit snugly and by reason of the fact that the band conforms substantially exactly to the shape of the leg forward movement of 110 the leg is prevented because such forward movement causes an enlargement of the

muscles of the leg at the point of attachment. Therefore the band will readily act as an anti-kicker as hereinbefore premised.

Passing now to the tail clamp, this is composed of the cooperating serrated or toothed jaws 7 and 8 normally held in closed position by the spring 9 and having the finger piece extensions 10 for opening the jaws to permit of engagement. The jaws are pivoted upon the pivot member 11 and that jaw designated 8, it will be observed in Figure 3, is substantially narrower than the other jaw so that it will seat within the latter, spacing washers 12 being provided upon the pivot 11 to hold the jaw in place. This arrangement of the jaw members permits the jaws to close upon the long hairs of the cow's tail which hairs will extend between the contiguous sides of the jaws and afford an efficient gripping engagement which tends to preventing any likelihood of displacement of the clamp from attempts on the part of the cow to move its tail. The fact that the clamp is connected to the leg

band by the flexible chain connection 3 permits of relative movement of the tail with respect to the leg.

A very efficient, simple article that may be cheaply manufactured is thus provided. Having thus described my invention, what I claim as new is:

A cow tail holder comprising an open band formed of a single strip of resilient material which is looped to completely encircle the leg and shaped to conform to the contour of the leg above the gambrel joint, said loop being elongated and having curved ends, one of the said curved ends being contracted to provide a seat which fits snugly about the gambrel cord so that it will tend to interfere with the movements of the muscles of the leg incident to kicking, fastening means for tightly clamping the band upon the cow's leg, and a tail engaging clamp operatively connected to the band. 45

In testimony whereof I affix my signature.

WILL F. JOHNSON.
